(57) **CLAIM**

The ornamental design for a camera lens clip, as shown and described.

DESCRIPTION

FIG. 1 is a front elevational view of the camera lens clip; the back elevational view is a mirror image of the front elevation view.

FIG. 2 is a right side elevational view of the camera lens clip; the left side elevational view is a mirror image of the right side elevational view.

FIG. 3 is a top view of a camera lens clip showing our new design.

FIG. 4 is a bottom view of the camera lens clip.

FIG. 5 is a bottom perspective view of the camera lens clip; and,

FIG. 6 is a right side perspective view of the camera lens clip; the left side perspective view is a mirror image of the right side perspective view.

The broken lines in the drawings depict parts of the camera lens clip that form no part of the claimed design.

1 Claim, 3 Drawing Sheets
